UNITED STATES PATENT OFFICE.

ALBERT C. MEYER, OF SAN DIEGO, CALIFORNIA.

HAND-STAMP RACK.

1,298,993.

Specification of Letters Patent.

Patented Apr. 1, 1919.

Application filed June 18, 1918. Serial No. 240,566.

To all whom it may concern:

Be it known that I, ALBERT C. MEYER, a citizen of the United States, residing at San Diego, in the county of San Diego and State 5 of California, have invented certain new and useful Improvements in Hand-Stamp Racks, of which the following is a specification.

My invention relates to hand stamp racks 10 of the type shown in my application filed September 4, 1917, Serial No. 189,607, allowed January 21, 1918.

The objects of the invention are as follows:

15 1. To provide improved means for adjusting the parallel crossbars on the side bars of the frame.

2. To provide these crossbars with a series of adjustable spacers, and finally to 20 provide a novel form of support for the end of the stamps.

These objects I accomplish by the construction shown in the accompanying drawing, in which:

25 Figure 1 is a sectional perspective of the rack and suspended stamps.

Fig. 2 is a detail perspective, showing one form of spacer.

Fig. 3 is a similar view of another form 30 of spacer.

Fig. 4 is a perspective of one of the supports separate from the stamp.

Fig. 5 shows a stamp provided with the improved support.

35 A designates a rectangular frame formed of angle metal; the top members of the sides of which are provided with longitudinal lines of perforations a , while the depending side flanges a' are provided with struck up 40 keepers a^2 a^2 at the front and rear to receive the tongues b b on the upper ends of the legs B. The legs B are thus firmly, though 45 removably, secured to the frame and are of a length to support the frame at the proper angle and height as in said prior application.

The stamp-supporting bars C are turned in along their side edges to form slideways for the labels D, as in said application, and 50 their ends are perforated, as at c. The bars C are spaced apart according to the thickness of the stamps E by means of headed pronged fasteners F, which may be ordinary paper fasteners. The legs of the fasteners 55 are passed down through the openings c a and bent apart, which is a very simple and

inexpensive manner of adjustably securing the bars C in place.

The bars C are provided with spacers G or G' formed of sheet metal or the like and provided at their upper edges with curved jaws shaped to fit the under sides and turned in edges of the bars C. In Fig. 2 the spacer is formed of an angle piece, the horizontal member g of which underlies the bar C, and has its longitudinal edges inturned to form 60 a slideway g' so as to be passed endwise upon the bar C and be held frictionally thereon at whatever point of adjustment may be desired, according to the width of the stamps E. In Fig. 3 the spacer G' is 65 formed at its upper edge with an open recess g^2 to correspond to the cross section of the bar C, thus adapting the spacer to be slid endwise on the bar and held by friction in its adjusted position. The openings thus 70 formed for the endwise insertion and removal of the stamps are both longitudinally and laterally adjustable so that stamps of different widths and thicknesses may be provided for.

80 The ends of the stamps E are provided with sheet metal supports E', each comprising a flat plate e to rest against the end of the stamp in the direction of the width and formed with penetrating prongs e' to 85 secure it in place. From the middle of this plate e depend two legs e^2 e^3 terminating at their lower ends in oppositely projecting feet e^4 adapted to rest upon the upper edges of two contiguous bars C, as shown in Fig. 90 1. These legs e^2 e^3 may be bent apart so as to receive the thickest stamps employed and at the same time span the wide openings formed in the frame for said thick stamps. The legs e^2 e^3 are of different lengths to allow for the inclination of the frame.

Transparent label covers may be provided as in my application before referred to.

What I claim is:

1. A hand stamp rack comprising an open 100 frame provided with parallel, adjustably-spaced stamp-supporting bars and transverse, sliding spacers mounted on said bars with their free ends extending across the spaces between the bars, for the purpose 105 set forth.

2. A hand stamp rack comprising, a rectangular frame having label receiving bars spaced apart the thickness of the stamps, and transverse sliding spacers mounted on 110

the bars and adjustable for the width of the stamps inserted endwise therebetween.

3. A hand stamp rack comprising an open rectangular frame having parallel stamp supporting bars spaced apart according to the thickness of the stamps, and spacers having guides at their upper ends shaped to slide endwise upon the bars to adjust the stamp receiving spaces to the width of the 10 stamps inserted endwise therein.

4. A hand stamp rack having openings for the endwise insertion and removal of the stamps and hand stamp supports, each comprising a plate having prongs to enter the 15 end of a stamp, and depending legs at opposite sides of the middle of said plate and adapted to be bent apart to receive stamps of different thicknesses and at the same time support the stamp.

5. In a hand stamp rack having openings 20 for the endwise insertion and removal of the stamps, a hand stamp support formed of a flat plate having prongs to enter the end of a stamp, and depending legs adapted to be bent apart for stamps of different thicknesses; said legs terminating in oppositely extending feet for the purpose described. 25

6. In a hand stamp rack, a stamp support formed of a flat plate having prongs to enter the end of a stamp, and depending legs 30 of different lengths at opposite sides of the middle of the plate; said legs adapted to be bent apart for the purpose described and terminating at their lower ends in oppositely extending feet to rest upon the upper 35 face of the rack.

In testimony whereof I affix my signature.

ALBERT C. MEYER.

Copies of this patent may be obtained for five cents each, by addressing the "Commissioner of Patents, Washington, D. C."
